UNITED STATES PATENT OFFICE.

WALDO SHELDON, OF GREENWICH, CONNECTICUT.

WELL DRILLING.

Application filed April 4, 1924. Serial No. 704,102.

This invention relates particularly to deep well drilling and the objects of the invention are to provide apparatus for this purpose which will enable accurate control of the 5 drill feeding operations, permitting pressure on the drill stem to be maintained constant, increased or decreased at will; which can be operated either with diamond drill bits or as a regular rotary drill; which will be free 10 of the objectionable gyratory action common to rotary drilling apparatus in use at the present time and which, furthermore, will be relatively simple in construction and practical in all respects.

15 The various novel features which make possible the attainment of the foregoing are set forth in the following specification.

The accompanying drawings, forming 20 part of this specification, illustrate a practical embodiment of the invention, but it is to be understood that the structure may vary without departure from the broad spirit and scope of the invention as hereinafter defined and claimed.

25 Figure 1 in the drawings is a side elevation and part sectional view of a form of the invention designed for drilling deep oil wells.

Figure 2 is a plan view of the main parts 30 of the same.

Figure 3 is a sectional view across the barrel of the table, taken substantially on the plane of line 3—3 of Figure 1.

Figure 4 is an enlarged broken sectional 35 detail of the thrust yoke bearings.

Figure 5 is a similar detail of the upper supporting bearing for the rotary table.

Figure 6 is a sectional view of a drive 40 bushing or adapter which can be used for holding the drill stem in the table when the apparatus is to be operated as a straight rotary.

The frame of the apparatus is shown as made up of I-beams 7 on which there is supported a bed 8. This bed may be in the 45 form of a flat steel plate, such as indicated, having a seat or opening 9 at the center for the base of the table and openings 10 at opposite sides of the same for the two power cylinders.

The table base consists in the main of a rigid tubular casing 11 extending down through the central opening in the bed plate and supported by a collar or shoulder 12 at 50 its upper end having a bearing on top of the bed plate.

The table 13 is shown as driven by the customary gearing 14—15, but this table differs from the usual form of construction by being provided with a dependent tubular 60 extension or bearing sleeve 16 which extends down into the guide casing 11 of the base and is journaled therein.

In the present disclosure two bearings are actually provided, one at the top of the casing, directly beneath the rim of the table and shown as a ball bearing 17 and the other at the lower end of the casing and shown as a plain bearing 18 on a bearing liner 19 set in the sleeve of the table base. The upper end of this liner is shown as providing a bearing at 20, for the upper end of the table sleeve below the ball bearing. This bearing construction provides for keeping the table running truly at all times.

75 In order to support a suitable quantity of lubricant in this lower table bearing, the bearing sleeve is shown as having an annular collar 21 attached to the lower end of the same, extending out beyond the lower 80 end of the casing and carrying an upstanding flange or casing 22 forming an annular lubricant well.

By means of this construction it will be seen that the table, while free to rotate, is 85 guided and positively held against any wobbling or gyratory movements. The upper and lower bearings are usually quite widely separated, for example, a matter of thirty inches or more, with the upper bearing 90 above or substantially at the level of the derrick floor and the lower bearing in the clear below the derrick floor where it can be reached for adjustment purposes.

Slidably keyed in the table sleeve is a 95 tubular chuck stem 23 carrying at its upper end a set of drill stem-engaging jaws 24 actuated by bolts 25. The keying engagement between the table sleeve and chuck stem is shown as effected by means of angular keys 100 26, engaged in longitudinal keyways 27 and 28 in the table sleeve and stem respectively.

The drill stem is indicated at 29 in Figure 1 held by the chuck jaws and guided at the lower end of the chuck stem by a correspondingly shaped bushing 30 slipped into the stem and removably supported on a flange 50 detachably secured to the lower end of the chuck stem.

A positively lifting and lowering force is 110 applied to the chuck stem for the purpose of raising or lowering the drill stem by a power

actuated head 31 held relatively rotatably on the chuck stem between spaced annular thrust shoulders 32, 33. Ball bearings 34 and bearing rings or cones 35 are indicated 5 interposed at these thrust shoulders to reduce the friction.

The upper thrust shoulder 32 is shown made as a separate part removably secured to the collar which carries the lower flange 10 or shoulder 33 by bolts 36. The chuck body 52 is shown removably secured to the flange 32 by bolts 53. This construction permits ready removal and the substitution of different forms of chucks, the ready inspection 15 and repair of the thrust bearings and when desired, complete removal of the yoke or non-rotating head 31.

The power applying head is shown constructed after the manner of a collar, 20 surrounding the chuck stem, having diametrically opposite projecting arms 37 provided with sockets 38 receiving the upper ends of the piston rods 39, rising at the sides of the table and having pistons 40 working in cylinders 41, supported below the level of the 25 table in the seats 10 in the bed plate.

The power cylinders are shown as outwardly flanged at their upper ends at 42 to seat on the supporting collars 43 and as 30 having covers 44 secured in place by the bolts 45 which pass through all these parts into the bed plate so as to both secure the parts together and removably fasten the power cylinders in position. Thus the removal of these bolts enables the detachment 35 of the cylinder head or the complete removal of the power cylinder from its seat in the bed plate.

The cylinder head is shown as constructed 40 with a deep seat in the center of the same to receive the packing 46 and the adjustable follower 47 which can be advanced to compress the packing by the nuts 48. This follower is of substantial length so as to 45 provide a bearing for the piston rod and so as also to provide a seat completely housing the end of the head when the same is lowered therein, as indicated in broken lines at the left in Figure 1. As a further protection 50 to the lowered end of the piston rod, an annular cap 49 is shown positioned over the entire packing gland structure.

The piston rods are shown as having a 55 readily detachable engagement with the non-rotating head of the chuck by means of angular keys 60 seated in correspondingly shaped alined openings in the ends of the arms 37 of the head and ends of the rods respectively. The ends of the rods where 60 they seat in the sockets 38 are shown as of reduced diameter and shouldered at 51. It will be evident that by knocking out the transverse keys 60, the power cylinders can 65 be entirely disconnected from the chuck and the pistons be lowered so that the rods are

housed within the cylinders and thus out of the way of all operations about the table.

Also if desired, the complete chuck structure, after disconnection from the power cylinders can be lifted out of the rotary table, 70 leaving the table free and clear for ordinary rotary drilling operations. For such purposes the outfit will usually be provided with one or a number of drill stem bushings such as the one illustrated at 55 in Figure 75 6 shown as seating partly in the bore of the rotary table and having a flange 56 resting on top of the table secured by bolts 57. This adapter is shown as having a tapered passage 58 to receive the "slips", drive bushings 80 or other drill engaging means. This passage, forming the seat for the drill stem clamp is shown as extending partly above the table, but in different forms of adapters which may be used with the table, such seat 85 may be disposed entirely above the table or located wholly within the bore of the table.

The admission of fluid under pressure to the power cylinders is controlled by suitable valve and piping connections, a part of 90 which are indicated at 54. By exercising a proper control the drilling force may be regulated as desired and the drill stem may be readily raised and lowered. When necessary the power cylinders can be quickly removed by unfastening the securing bolts and then simply hoisting them out of their seats in the bed plate; similarly, the table may be lifted out of its base after the stop flange 21 has been detached from the lower end of 100 the same.

The construction disclosed overcomes 105 gyroscopic tendencies and keeps the drill stem balanced and running straight and true. The pressure on the drill stem may be maintained uniform or be instantly varied and to any desired extent, to suit changing conditions. The fineness of control which the invention makes possible is particularly important when operating with diamond 110 bits and the like, where great accuracy of feed is essential to successful operations.

The long bearings for the piston rods provided by the inverted stuffing glands 115 keep the piston rods parallel and are particularly useful in overcoming the twisting effort exerted on the yoke when the piston rods are projected to their fullest extent. The removal of the chuck and yoke construction and the lowering of the piston rods 120 into the power cylinders leaves the rotary table free and unimpeded so that the same may be used for any ordinary or special drilling operations and so that the way is clear for using the wrenches, clamps and any 125 other tools which may be found necessary or useful for such operations.

The removability of the chuck body 52 is a particularly important feature in that it enables the substitution of adapters and 130

- bushings such as used in regular drilling operations. This it will be seen makes the invention fully adaptable for all kinds of rotary and diamond drilling operations and 5 the hydraulic feed provides a more refined and accurate control which can be used either as the sole feeding means or be used in conjunction with the ordinary cable hoist method of feeding. Also when desired the 10 cable feed may be used alone. The apparatus is thus universally adaptable for all kinds of conditions and requirements which may be encountered in rotary and diamond drilling operations.
- 15 The chuck also may be used in place of a "rod brake" to control the drill stem while coming out of the hole under pressure. Thus the apparatus may be used for bringing in a well and for taking the drill stem out 20 under pressure. The power of the pressure cylinders may be used to hold the drill stem while it is coming out under pressure after the manner of a snubbing device and if desired, smooth chuck jaws may be employed 25 and their pressure regulated to act as brakes on the drill stem.
- What is claimed is:
1. In a well drilling apparatus, supporting beams, a bed plate supported on said 30 beams, an elongated rigid large diameter bearing sleeve dependent from said bed plate between the beams, a rotary table having a large rigid elongated dependent sleeve journaled in the dependent bearing sleeve 35 of the bed plate, a tubular chuck stem slid- ily keyed in the dependent sleeve of said rotary table, drill stem gripping means carried by the upper end of said tubular stem, a pressure applying head having a relatively 40 rotatable engagement with said tubular stem and power mechanism sustained from the bed plate between the beams and connected with said head.
  2. In well drilling apparatus, supporting 45 beams arranged in spaced relation, a flat bed plate supported on said beams and having an opening therethrough between the beams large enough to pass both the well casing and the drill pipe, a rigid bearing sleeve seated in said opening and dependent 50 from the bed plate between said beams and a flat top full size rotary table having a sup- 55 porting bearing directly beneath the same and provided with a long dependent sleeve journaled in the lower end of the bearing sleeve below the supporting beams, whereby 60 said table is guided both above the bed plate and below the supporting beams so as to rotate truly and overcome gyroscopic forces.
  3. In well drilling apparatus, a rotary 65 table having an elongated bearing sleeve, a base having an elongated casing in which said sleeve is journaled, a tubular chuck stem slidingly keyed in the table sleeve, drill 70 stem engaging means carried by said stem, a pressure applying head having a relatively 75 rotatable engagement with the chuck stem, power mechanism connected with said head, the table having a bearing at the top of the bearing sleeve and another at the bottom of the bearing sleeve to rotatably support the table sleeve at widely separated points and a surrounding casing for retaining lubricant in said lower bearing.
  4. In well drilling apparatus, a rotary 80 table having an elongated bearing sleeve, a base having an elongated casing in which said sleeve is journaled, a tubular chuck stem slidingly keyed in the table sleeve, drill stem engaging means carried by said stem, a pressure applying head having a relatively 85 rotatable engagement with the chuck stem, power mechanism connected with said head, said table base and power mechanism being all mounted on a flat bed plate mounted directly on I-beams.
  5. In well drilling apparatus, the combination with four supporting beams ar- 90 ranged in spaced parallel relation, a bed plate mounted on said beams and having openings in line with the spaces between the beams, a supporting casing seated in the central opening and having an elongated dependent bearing sleeve and a rotary table having a dependent elongated sleeve jour- 95 naled in said bearing sleeve, of a chuck sleeve slidably keyed in said table so as to be rotated thereby irrespective of vertical ad- 100 justment of the sleeve through the rotary table, drill stem gripping means carried by said chuck sleeve for adjustable engagement with a drill stem extending through the sleeve and table, controllable power cylinders seated in the side openings and oper- 105 able irrespective of the rotation of the table and power applying connections from said power cylinders to the chuck sleeve, includ- 110 ing relatively rotatable engaging means enabling application of accurately regulat- 115 able lifting and lowering force to the drill stem during operation of the rotary table.
  6. In well drilling apparatus, supporting 120 beams, a substantially flat bed plate mounted on said beams, a rotary table having an elongated bearing sleeve, a base car- 125 ried by said bed plate having an elongated casing dependent between the beams and in which said sleeve is journaled, a tubular chuck stem slidingly keyed in the table sleeve, drill stem engaging means carried by said stem, a pressure applying head hav- 130 ing a relatively rotatable engagement with the chuck stem, power mechanism mounted on the substantially flat bed plate and de- 135 tachably connected with said head, said chuck stem being disconnectible from the power mechanism and withdrawable from the table sleeve to leave the same clear for the mounting of adapters or the like for regular rotary drilling.

7. In well drilling apparatus, a bed plate for a rotary table, said bed plate having an opening for seating a table of sufficient size to pass the casing which is to be used about 5 the drill pipe, a rotary table having a bore of sufficient size to pass the casing, said table being rotatably seated in said bed plate, a drive sleeve slidably keyed in said table and entirely withdrawable therefrom 10 to leave the table clear for regular rotary drilling operations, drill pipe driving means carried by the upper end of said sleeve but readily removable therefrom, annular thrust shoulders on the drive sleeve above the table 15 but below said removable drill pipe driving means, a yoke having relatively rotatable engagement with said thrust shoulders and provided with outstanding arms projecting beyond the edges of the table, power cylinders supported below and at opposite sides of the table, pistons in said cylinders having piston rods rising past the edges of the table and keys for securing the upper ends of said piston rods in readily detachable engagement 20 with the outstanding arms of the yoke.
8. In combination with the spaced beams, a bed plate supported thereon and provided with an intermediate and two side openings, a table base having a casing extending down 25 through the intermediate opening between two of the beams, power cylinders dependent through the side openings between other beams, a table having a dependent bearing sleeve journaled in the casing, a chuck stem 30 slidably keyed in the table sleeve, drill stem engaging means carried by said chuck stem, a power applying head having a relatively rotatable engagement with the chuck stem and piston rods rising from the power cylinders and detachably connected with the head 35 of the chuck.
9. In well drilling apparatus, a rotary table, a drive sleeve slidably keyed therein, a pressure applying yoke having a relatively 40 rotatable engagement with said sleeve, power mechanism connected with said yoke for raising and lowering the drive sleeve independently of the rotation imparted thereto by the table, drill pipe driving 45 means removably secured at the upper end of said drive sleeve for imparting the rotary and vertical movements of the sleeve to a drill pipe extending therethrough and a bushing removably supported in the lower 50 end of the drive sleeve and having only a guiding engagement with the drill pipe.
10. In well drilling apparatus, a bed plate, a table base removably seated in said bed plate, power cylinders seated in the bed 55 plate at opposite sides of the table base, a rotary table journaled in the base, a tubular chuck stem slidably keyed to the rotary table and provided with a non-rotating head and pistons in the power cylinders provided 60 with rods projecting up at the sides of the 65 table and detachably engaged with the non-rotating head of the chuck.
11. In combination, a bed plate having intermediate and two side openings, a table base secured on the bed plate having a casing extending down through the intermediate opening, power cylinders secured on the base plate and extending down through the side openings, a table having a dependent bearing sleeve journaled in the casing and 70 piston rods in the power cylinders extensible up at the sides of the rotary table and adapted for lowering in the cylinders out of the way of the rotary table.
12. Well drilling apparatus including a 75 rotary table, a chuck construction slidably keyed thereto, a yoke engaged relatively rotatably with the chuck construction, power cylinders at the side of the rotary table having inverted packing glands with 80 elongated piston rod bearings, pistons in the cylinders having piston rods operating through said elongated bearings, means for connecting said piston rods with the yoke, said last mentioned means constructed to 85 enable detachment of the piston rods from the yoke whereby the latter may be lowered in the cylinders until the upper ends of the rods are housed in the elongated bearings and protective caps over the upper ends of 90 the cylinders for guarding the piston rods in their lowered positions.
13. In well drilling apparatus, the combination of supporting beams, a substantially flat bed plate mounted on said beams 100 and provided with an intermediate and two side seats between the beams, a large diameter rotary table having a long dependent bearing sleeve journaled in the intermediate seat of the bed plate, power cylinders supported in the side seats of the bed plate dependent between the beams and located at opposite sides of the rotary table, pistons operating in said cylinders and having piston rods rising above the 105 bed plate at opposite sides of the table, a cross beam detachably mounted on the upper ends of said piston rods, a large diameter drive sleeve journaled in said cross beam and having a sliding driven engagement in the elongated bearing sleeve of the table, said drive sleeve being shouldered to rest upon and be supported by the table when the pistons are lowered in their cylinders and adjustable drill pipe gripping 110 means removably secured to the upper end portion of the drive sleeve and accessible for adjustment or removal purposes over the top of the table when the drive sleeve is lowered into supported position upon the 115 table.
14. In well drilling apparatus, the combination of a substantially flat rigid bed plate provided with a large diameter seat for a rotary table and power cylinder seats 120
- 125
- 130

at opposite sides of said table seat, a large diameter rotary table having an elongated bearing sleeve journaled in the table seat and dependent from the bed plate, power 5 cylinders mounted in the two side seats of the bed plate and dependent from said bed plate, beams supporting the bed plate and spaced for passage of the dependent portions of the table sleeve and power cylinders, pistons in the cylinders having projecting piston rods, a beam extending transversely of the table and detachably connected with said piston rods, a drive sleeve 10 extending through the bearing sleeve of the table and journaled in the cross beam, pipe 15 gripping means carried by said sleeve and adjustable to grip drill pipe extending down through the sleeve and means for releasably keying the drive sleeve in the dependent bearing sleeve of the table for causing the 20 drive sleeve to rotate with the table or to remain at rest in respect to the rotation of said table.

In witness whereof, I have hereunto set my hand this 19th day of March, 1924.

WALDO SHELDON.
